UNITED STATES PATENT OFFICE.

GEORGE KYNOCHE, OF WITTON, NEAR BIRMINGHAM, COUNTY OF STAFFORD,
ENGLAND.

CARTRIDGE-SHELL.

SPECIFICATION forming part of Letters Patent No. 298,696, dated May 13, 1884.

Application filed January 9, 1882. (No model.) Patented in England November 1, 1881, No. 4,776.

To all whom it may concern:

Be it known that I, GEORGE KYNOCHE, a citizen of England, residing at Witton, near Birmingham, in the county of Stafford, England, have invented a new and useful Improvement in Cartridge-Cases, (for which I have applied for Letters Patent in Great Britain, bearing date November 1, 1881, No. 4,776,) of which the following is a specification.

10 My invention relates to the construction of metallic cartridge-cases in such a manner as to secure great soundness and durability consistently with great lightness of material and economy of manufacture.

15 The construction which I will describe applies to cartridge-cases, whether for sporting or for military purposes, as I will explain, referring to the accompanying drawings.

Of these Figures 1, 2, 3, 4, and 5 relate to a 20 common form of case for sporting-cartridges, and Figs. 6, 7, 8, 9, and 10 to a well-known form of case for military cartridges.

25 For cartridge-cases of other forms and proportions a like construction is applicable, as may be readily understood.

I make the cartridge-case in two parts, the tube and the head; but instead of making the tube, as in many kinds of composite cartridge-cases, without a bottom, or with a hole through 30 its bottom, and then securing it to the head by pulp or otherwise, I make the tube, by drawing in the ordinary way, with a complete bottom indented with a recess to receive the inwardly-projecting percussion-chamber of 35 the head. Figs. 1 and 6 show in longitudinal section the tube thus prepared. As the head, which I will presently describe, strengthens the bottom, I do not require to make the bottom of the drawn tube itself of considerable 40 thickness relatively to the tube, and consequently, as the tube is of nearly uniform thickness throughout its whole substance, I am enabled to draw it very thin without exposing any parts of it to unequal strains. I prepare, 45 by punching and drawing, a cup—such as those shown in Figs. 2 and 7—which cup is to form the head of the cartridge-case, and which has formed in it the inwardly-projecting percussion-chamber. Having prepared the tube, as

shown in Figs. 1 and 6, and the cup, as shown 50 in Figs. 2 and 7, I insert the bottom of the tube into the cup, as shown in Figs. 3 and 8, and I then subject the two together to drawing and heading pressure, so as to give the finished form shown in Figs. 4 and 9, the cup being by this 55 operation soundly united to the tube. Holes are then pierced, as shown by the plans, Figs. 5 and 10, for passage of flame from the percussion-cap into the charge, and the case is complete, ready for charging. The finished 60 cartridge-case thus manufactured, without requiring any internal lining, presents a strong double bottom, consisting of the inner thin bottom, which is of one piece with the tube, and of the outer thicker bottom, which is sufficiently strong to sustain the percussion, and which has the usual projecting lip or flange 65 for extraction. As the inner bottom is in one piece with the tube, there is no joint at the angles of the bottom liable to produce fracture 70 or to permit escape of powder-gas.

Heretofore a metallic cartridge-case having a closed end with a central depression in the latter has been provided with a cap, also formed with a central depression, the said cap 75 being fitted on the closed end of the case, with an elastic disk intervening between the closed end of the case and the cap. It will be seen, however, that I dispense with the interposed disk which prevents a close union between the 80 case and the cap, the latter being made by me of accurately the same configuration as the base or closed end of the case; also, after fitting on the cap, the two are subjected to drawing and heading pressure, whereby the 85 parts unite, so as to practically form one shell; but in the instance where the interposed disk is employed the cap must, to give it a firm hold on the case, be subjected to compression, such as will reduce the diameter both of the 90 cap and the base of the tubular shell.

Having thus described the nature of my invention and the best means I know of carrying it out in practice, I claim—

The improvement in the art of manufacturing cartridge-shells, which consists in making the shell or tube with a complete bottom having a central recess and applying thereto an exter- 95

nal flanged head provided with an inwardly-projecting nipple, forming the percussion-chamber; and then subjecting the parts thus connected to a drawing and heading pressure, whereby the cap is made to closely fit the configuration of the bottom of the tube or shell and the two parts are intimately united with each other, substantially as described.

In testimony whereof I have signed my name to this specification, in the presence of two subscribing witnesses, this 18th day of November, A. D. 1881.

GEO. KYNOCH.
